UNITED STATES PATENT OFFICE.

WILBURN ADOLFUS GALLEMORE, OF SOUTH CLINCHFIELD, VIRGINIA.

REBORING-MACHINE.

1,375,839.

Specification of Letters Patent. Patented Apr. 26, 1921.

Application filed February 5, 1920. Serial No. 356,449.

To all whom it may concern:

Be it known that I, WILBURN A. GALLEMORE, a citizen of the United States, residing at South Clinchfield, in the county of 5 Russell and State of Virginia, have invented a new and useful Reborning-Machine, of which the following is a specification.

This invention relates to new and useful improvements in reboring machines, and 10 more particularly to machines of this character especially designed for reboring cylinders in the event that the same become scored or otherwise rendered inoperative.

The primary object of the invention is to 15 provide a device of this character which may be readily and easily applied to an engine cylinder, while the same is in place on the engine base, thus eliminating the necessity of removing the cylinder to accomplish 20 the reboring thereof.

A further object of the invention is to provide a device of this character which will insure the cutting blades being maintained in proper cutting relation with the 25 walls of the cylinder, when the same are being forced through the cylinder.

A still further object of the invention is to provide means for automatically feeding the cutting blades through the cylinder, 30 when the same are being rotated to perform the cutting operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 40 within the scope of what is claimed, without departing from the spirit of the invention.

Referring to the drawings:—

Figure 1 illustrates a side elevational view of the boring machine as applied to a 45 cylinder, the cylinder being shown in cross section.

Fig. 2 illustrates a top plan view of the cutting machine, the handle being shown as partly broken away.

Fig. 3 illustrates a longitudinal sectional view of the boring machine, taken on line 50 3—3 of Fig. 2.

Fig. 4 illustrates a sectional view taken on line 4—4 of Fig. 3.

Fig. 5 illustrates a sectional view taken 55 on line 5—5 of Fig. 4.

Referring to the drawings in detail, the

device includes a supporting rod 5 having a threaded portion 5' extending from one end thereof, and terminating substantially 60 intermediate its length, the opposite end of the supporting rod 5 having a reduced threaded portion 6, to receive the apertured disk 7, which disk is secured to the rod 5 by means of the nut 8. 65

Supported on the rod 5, is the tubular member 9 which is of a length less than the length of the supporting rod 5, to permit the tubular member 9 to move longitudinally of the rod 5 for purposes to be hereinafter more fully described. Formed integral with one end of the tubular member 9 is a blade supporting head 10 having a plurality of grooves 11 formed in the under surface thereof which grooves are provided 75 for supporting the cutting blades 12, which as shown, are secured in the grooves by means of the wedge members 13, which members are held in position by means of the bolts 14 operating through suitable openings in the lugs. 80

As shown, each of these cutting blades 12 is provided with an inclined surface coöperating with an inclined surface 15 provided on the respective members 13. It will thus 85 be seen that when the bolts 14 are moved to draw the members 13 within their openings, the cutting blades 12 are secured against displacement from the grooves in which the same are positioned. 90

This head 10 is of a diameter slightly less than the diameter of a predetermined standard sized cylinder, so that the blades 12 may extend beyond the periphery of the circular head 10 to permit the blades to cut, 95 when the head 10 is moved longitudinally of a cylinder.

In order that the tubular member 9 may move freely over the supporting rod 5, a bushing 16 has connection with the tubular 100 member 9 and head 10, which bushing is also provided with an angular slot 17 extending throughout its length for receiving a lubricating medium, to facilitate the operation of the device. 105

The upper extremity of the tubular member 9 is threaded as at 18 to coöperate with the threads 19 formed on the follower 20, which is also provided with threads 21 adapted to coöperate with the threaded extremity 5' of the rod 5.

Associated with the tubular member 9 is the operating lever 23 having the ratchet head 24, which head is designed to embrace

the tubular member 9, to grip the same for causing the rotation of the tubular member 9 with the result that the follower 20, moving over the threaded portion 22 of the supporting rod 5 forces the tubular member 9, together with its head and cutting blades 12, toward the disk 7.

As shown, by Fig. 3 of the drawings, the disk 7 has a beveled periphery 25 adapted 10 to position itself within the open, or lower end of the cylinder to which the device is applied so that the supporting rod 5, is maintained in an upright position within the cylinder under operation, to the end that 15 the cutting blades 12 are held in proper operative relation with the walls of the cylinder.

Positioned on the tubular member 9 is a head 26, which head has a flange 27 formed 20 at the base thereof for contacting with the upper edge of a cylinder, there being provided bolts 28 for securing the head 26 to the cylinder, as indicated by Fig. 1 of the drawings.

25 Movement of the supporting rod 5, with relation to the head 26 is prevented by means of the relatively long bracket member 29 having its lower extremity bent at right angles as at 30, and apertured to receive the bolt 31, whereby the bracket 29 is secured to the head 26, the upper end of said bracket 29 having a right angled end 32 which is forked to engage within the groove 33 formed in the head 34, which in turn is 35 positioned on the extreme upper end of the threaded portion 22 of the supporting rod 5.

It might be further stated that a groove 35 is formed longitudinally of the tubular member 9, and receives a lug formed on the 40 ratchet head 24 so that movement of the ratchet head 24 is imparted to the tubular member 9 to cause the rotation thereof.

In the operation of the device, the head of a cylinder to be bored is removed, the 45 piston and rod is also removed and the supporting rod 5 extended upwardly through the cylinder until the disk 7 contacts with the inner walls of the cylinder adjacent the lower end thereof.

50 The tubular member 9 is now positioned on the rod 5 and the head 26 is moved over said tubular member 9 and secured to the upper end of the cylinder.

After the blades 12 have been adjusted to 55 a predetermined degree to permit the same to properly cut, the operating lever is rocked over the tubular member 9, with the result that the tubular member 9 together with the cutting blades 12 is moved through the cylinder with the result that portions of the cylinder are evenly and accurately removed.

It follows that when the head 10 has 60 reached a point adjacent the disk 7, the operator places his hand on the nut 34 to prevent rotation thereof, and it will be seen that

further rotation of the operating lever 23 operates to move the threaded portion 5' thereof downwardly through the nut 34, with the result that the supporting rod 5 drops through the cylinder being bored, and 70 the cylinder is resurfaced throughout its entire length.

Having thus described the invention, what I claim as new is:—

1. In a boring machine for reboring cylinders, a supporting rod having a disk on one end thereof, said disk having inclined surfaces to cause the same to seat within one end of the cylinder, a tubular member supported on the supporting rod, cutting blades 80 carried by the tubular member, a relatively large head positioned on the tubular member and adapted to be secured to the upper surfaces of a cylinder, means for rotating the tubular member and cutting blades, a 85 bracket member having connection with the relatively large head and having a right angled upper extremity, a threaded head positioned in the right angled upper extremity, said supporting rod having a threaded portion 90 extending through the threaded head, and said rod adapted to be threaded through the threaded head where the same drops through the cylinder.

2. In a boring machine for reboring cylinders, a supporting rod, means for securing the supporting rod within a cylinder, a bracket forming a part of the machine, means carried by the bracket and adapted to receive one end of the supporting rod, a tubular member adapted to move on the supporting rod, means for rotating the tubular member to cause the supporting rod to fall through the cylinder, when the lower end of the tubular member reaches the base 105 of the cylinder.

3. In a boring machine for reboring cylinders, a supporting rod, means carried at one end of the rod for securing the same within a cylinder, a tubular member carrying cutting blades and mounted on the supporting rod, said supporting rod having an upper threaded portion, a bracket member extending in parallel relation with the supporting rod and having a right angled extremity, a 115 threaded head carried by the bracket member and adapted to receive the threaded portion of the supporting rod, means for rotating the tubular member, and said means adapted to rotate the supporting rod to 120 cause the same to disengage the threaded head, when the tubular member reaches the lower end of the cylinder.

In testimony that I claim the foregoing as my own, I have hereto affixed my signature in the presence of two witnesses.

WILBURN ADOLFUS GALLEMOUE.
